UNITED STATES PATENT OFFICE.

ALEXANDER BOGUSZEWSKI, OF PSZENECZNIKI, RUSSIA.

APPARATUS FOR SEPARATING OR SORTING GRAIN, &c.

SPECIFICATION forming part of Letters Patent No. 627,970, dated July 4, 1899.

Application filed January 9, 1899. Serial No. 707,809. (No model.)

To all whom it may concern:

Be it known that I, ALEXANDER BOGUSZEWSKI, a subject of the Czar of Russia, residing at Pszeneczniki, in the Province of 5 Kiew, Russia, have invented certain new and useful Improvements in Apparatus for Separating or Sorting Grain, Granular Materials, and the Like, (for which I obtained German Letters Patent, dated June 11, 1898; Austrian 10 Letters Patent No. 48/4,425, dated July 14, 1898, and Hungarian Letters Patent No. 13,264, dated July 14, 1898,) of which the following is a specification.

My invention has relation to an apparatus 15 or device for separating and sorting grain, granular materials, or the like, and in such connection it relates more particularly to the construction and arrangement of such an apparatus or device.

20 The principal object of my invention is to provide a grain separating or sorting apparatus of simple construction and comprising, essentially, a vertically-arranged shaft or standard around which is coiled a series of 25 spirally-arranged channels or ways in nested relationship and of increasing diameter of spiral from the upper to the lowermost of the ways in series, said channels or ways being adapted for the reception of smaller and less 30 rounded grains or granules, and in conjunction with these spiral channels or ways a second spiral trough or channel is coiled around the shaft and of sufficient diameter to inclose all the spiral ways in series and to provide 35 in addition a separate way or channel wherein the larger and more rounded grains or granules are received.

My invention, stated in general terms, consists of a grain or analogous separating or 40 sorting apparatus constructed and arranged in substantially the manner hereinafter described and claimed.

The nature and scope of my invention will be more fully understood from the following 45 description, taken in connection with the accompanying drawings, forming part hereof, in which—

Figure 1 is a side elevation of a grain separating and sorting apparatus embodying main 50 features of my invention, and Fig. 2 is a similar view of the shaft or standard and the internal spiral channels or ways removed

from the external spiral trough and feeding-hopper.

Referring to the drawings, *a* represents a 55 vertically-arranged shaft or standard, around which is coiled a series of spirally-arranged channels or ways *b*, *b'*, *b²*, and *b³* in nested relationship and of increasing diameter of spiral from the upper channel *b* to the lower 60 channel *b³* in the series. These internal spiral channels or ways terminate in a common chute or exit *c*. To the upper end of the shaft or standard *a* is secured a feed-hopper *d*, the base of which is open and controlled 65 by a slide *d'*. Around the shaft or standard *a* is also coiled a spiral trough *e*, which incloses the internal spiral channels and is provided with a vertical flange *e'* at its outer edge and terminates in a chute or gutter *f*, 70 located, preferably, diametrically opposite to the chute or exit *c* of the internal spiral ways *b*, *b'*, *b²*, and *b³*.

The operation of the device may be briefly described as follows: The unsorted material 75 in the hopper *d* is discharged or distributed evenly over the internal spiral ways or channels *b*, *b'*, *b²*, and *b³*, and the smaller particles enter these ways or channels and travel downward thereon until discharged from the chute or exit *c*. In this travel the larger particles which may be forced from the channel *b* will be caught by the next channel *b'*, the diameter of whose spiral is enlarged for that purpose, and so on. Those particles which are too 80 large for the larger spiral way *b³* are caught in and conducted by the spiral trough *e* and discharged through the chute or gutter *f*.

The apparatus is especially adapted for 85 the sorting or separating of grain which is of oblong or ellipsoidal shape from rounded objects, such as peas or beans, since in the discharge of the mixed grain and foreign materials the internal spiral ways will catch and hold the oblong or ellipsoidal grains, whereas 90 by centrifugal force the rounded grains, such as peas and the like, will roll over the internal spiral ways and enter the external spiral trough *e*.

Having thus described the nature and object of my invention, what I claim as new, and desire to secure by Letters Patent, is—

In a separating or sorting apparatus for grain and granular materials, a vertically-

arranged shaft or standard, a series of spiral channels or ways coiled around said shaft or standard, said spiral channels being arranged in nested relationship and having the channels or ways of increasing diameter of spiral from the uppermost to the lowermost of the channels or ways in series, and an external spiral trough coiled around said shaft and of sufficient diameter to inclose all of the internal spiral channels and to form a separate way for the reception of granules larger than

those which enter the internal spiral channels, substantially as and for the purposes described.

In testimony whereof I have hereunto set my signature in the presence of two subscribing witnesses.

ALEXANDER BOGUSZEWSKI. [L. S.]
